UNITED STATES PATENT OFFICE.

SIMEON C. LAWLOR, OF CHICAGO, ILLINOIS, ASSIGNOR OF ONE-HALF TO NICHOLAS
WETZEL, JR., OF CHICAGO, ILLINOIS.

CASTER-CLAMP FOR PAILS.

1,200,954.

Specification of Letters Patent. Patented Oct. 10, 1916.

Application filed May 3, 1912. Serial No. 694,948.

To all whom it may concern:

Be it known that I, SIMEON C. LAWLOR,
a citizen of the United States, residing at
Chicago, in the county of Cook and State
5 of Illinois, have invented certain new and
useful Improvements in Caster-Clamps for
Pails; and I do hereby declare the follow-
ing to be a full, clear, and exact description
of the invention, such as will enable others
10 skilled in the art to which it appertains to
make and use the same.

This invention relates to improvements in scrubbing pails, and more particularly to the mounting or support thereof.

15 The object in view is the provision of an
adjustable carriage or support for a pail
of the class mentioned, which carriage shall
be both simple and efficient in construction
and operation and at the same time adapt-
20 ed for application to pails of different di-
ameters.

With this and further objects in view, the invention comprises certain novel constructions, combinations and arrangements of parts as will be hereinafter described and claimed.

In the accompanying drawing, Figure 1 is a perspective view of a structure embodying the features of the present invention. Fig. 2 is a transverse vertical section through a part of the clamping band, the section being taken substantially centrally of one of the caster brackets. Fig. 3 is a similar section taken on a plane approximately centrally of one of the underhanging hooks. Fig. 4 is a top plan view of the clamping band and connected parts detached from the pail.

Referring to the drawing by numerals, 1 indicates a pail surrounded adjacent its lower end by a clamping band consisting of sections 2, 2, and adjustable connections therefor for varying the diameter of the band by varying the distance between adjacent ends of the several sections. Such adjustable connections may assume various embodiments, a simple and efficient embodiment being illustrated and consisting of a bolt 3, passed through outstanding eyes 4, 4 of adjacent ends of section 2, the bolt being provided with a head at one end engaging one eye, and a nut 5 at the other end engaging the other eye. Each section 2 is provided at each end with an eye 4, and a bolt 3 is provided for each pair of ad-

jacent eyes. As many sections 2 may be employed as required for surrounding the particular pail or receptacle, and it will be seen that the clamping band is thus adaptable to pails of varying sizes within quite a wide range. Each section 2 is provided with a caster bracket supplied with a caster 6 so that when the sections are connected to form a complete band and are tightened about a pail by drawing up on the nuts 5, the pail clamped within the sections will be supported on casters and thus rendered easy to move about the floor. Each of the caster brackets may consist of a strap bent into U-shape, as indicated at 7, with the intermediate portion of the U riveted or otherwise fixed to the section 2, and the outstanding arms of the U apertured to form vertically aligned bearings for the shank or shaft of the respective caster 6, the upper end of the shank being preferably swaged or otherwise enlarged for preventing accidental displacement of the shank from the arms of the bracket 7. Each section 2 is formed with a depending hook or hooks 11 positioned for underhanging the lower edge of the pail 1 for positively supporting the pail and avoiding the necessity for depending on the frictional engagement of the clamping band.

It has been proposed to supply scrubbing pails with mop wringers or wringing apparatus provided with foot levers, and I find it desirable with some of such levers which extend beyond the pail to provide means for steadyng the pail, and in the present construction I employ a caster bracket of somewhat modified form from that above described, consisting of a strap formed into a horizontal portion 12, an upright portion 13, an upper horizontal portion 14, and an inclined portion 15 connecting the upper horizontal portion 14 with the outer end of the lower horizontal portion 12, the inclined portion being formed with a horizontal offset toward its lower portion. A caster 16 has its shank journaled in the outer part of the horizontal portion 12 and in the offset of portion 15. The upright portion 13 extends from the inner end of horizontal portion 12 and is formed with an inwardly extending hook 17 spaced above the horizontal portion 12 a distance proportionate to the height required according to the form of the other caster brackets employed. A rod 18 is pro-

vided with a hook 19 adapted to overhang the upper edge of pail 1, and the horizontal portion 14 is apertured and through the aperture extends the rod 18. The lower end 5 portion of rod 18 is threaded and is engaged by a nut 20 beneath the horizontal portion 14, whereby when the parts are in the position indicated in Fig. 1, the nut 20 may be threaded upwardly for clamping 10 the parts firmly together, or the nut 20 may be threaded downwardly, the hook 19 removed from the upper edge of the pail, and the guiding bracket thus readily removed. It is to be observed that regardless of the 15 size of the receptacle to which the clamping band may be applied, each section of the band will contribute a support in the form of a caster, so that when the band is in place on any given receptacle, the receptacle is 20 adequately supported whether three sections have been employed or a much greater number, the points of support being increased in number proportionately to the number of sections employed and consequently proportionately to the size of the receptacle to be 25 sustained. Each section 2 consists of a strip, preferably of strap metal, and each section may be considered an article of manufacture in itself, and when so considered, to be complete should be provided with the caster bracket or its equivalent and in most instances with the underhanging hook.

It will be observed that the caster bracket 35 which carries caster 16 is constructed to cause the caster to stand out from the receptacle or pail, so that when the lever of the wringing mechanism is depressed the pail will be steadied, that is will be supported against the tendency to tilt in the 40 direction of the applied pressure.

What I claim is:—

1. The combination with a pail, of a

clamping band adapted to surround the same and comprising endwise disposed sections adjustable relative to each other, and adjustable connections for adjacent ends of said sections for completing the clamping band, a support connected to each section extending below the plane of the bottom of 45 the pail, means for connecting each section to the upper portion of the pail, and a hook extending from each section and underhanging the pail.

2. The combination with a pail, of a 50 caster bracket outstanding therefrom, a caster journaled in the outstanding portion of the bracket, a rod having an adjustable connection to the bracket and extending upwardly therefrom and formed with pail 60 engaging means at its upper portion, and an underhanging hook extending inwardly from the bracket.

3. The combination with a pail, of a 55 clamping band surrounding the pail, supports outstanding from the band, and a support connected to the pail and band and outstanding therefrom a greater distance than the other supports.

4. The combination with a pail, of a 60 caster bracket outstanding therefrom, a caster journaled in the outstanding portion of the bracket, a rod connected to the bracket and having means of engagement with the upper portion of the pail, and 75 means connected with and extending below the bracket adapted to engage the lower portion of the pail for connecting the bracket thereto.

In testimony whereof I affix my signature in presence of two witnesses.

SIMEON C. LAWLOR.
